WILLIAM E. OSTERHOUT, OF BROOKLYN, NEW YORK, AND EWING K. LYNN, OF EAST MCKEESPORT, PENNSYLVANIA, ASSIGNEES TO WESTINGHOUSE ELECTRIC & MANUFACTURING COMPANY, A CORPORATION OF PENNSYLVANIA.

SHORT-CIRCUITING SWITCH.

Application filed February 4, 1921, Serial No. 442,386. Renewed March 17, 1924.

To all whom it may concern:

Be it known that we, WILLIAM E. OSTERHOUT, a citizen of the United States, and a resident of Brooklyn, in the county of Kings and State of New York, and EWING K. LYNN, a citizen of the United States, and a resident of East McKeesport, in the county of Allegheny and State of Pennsylvania, have invented a new and useful Improvement 10 in Short-Circuiting Switches, of which the following is a specification.

Our invention relates to centrifugally actuated short-circuiting devices for dynamo-electric machines, and it has particular 15 relation to single-phase motors of the commutator type that are adapted for repulsion operation during the starting operation and for induction operation after a predetermined speed has been attained.

One object of our invention is to provide 20 simple, effective and inexpensive centrifugally actuated means for operating a short-circuiting device of the above designated character.

Another object of our invention is to provide 25 contact mechanism of a satisfactory type that shall be adapted to be mounted upon the commutator cylinder whereby certain segments thereof may be readily short-circuited.

Another object of our invention is to provide 30 a mechanism whereby the pressure exerted by the short-circuiting means upon the co-operating contact members shall be maintained substantially constant, irrespective of the speed of the machine, and of sufficient force to insure a good contact therebetween.

Heretofore, it has been customary, in the 35 construction of short-circuiting devices for commutators, to move a short-circuiting member axially into engagement with the ends of the commutator bars. Another type of construction employed is that in which a disk is moved both axially and rotatably in- 40 to engagement with the ends of the commutator bars.

Our present invention differs from those 45 previously described in that a disk of insulating material has spaced conducting members imbedded therein that are connected together electrically by an annular conducting member which is moved circumferentially when the machine attains a prede-

termined speed. Means are provided whereby the pressure on the disk remains constant at all times, thus insuring that a good contact shall be made between the short-circuiting member and the imbedded contact members. 55

In the accompanying drawings, Figure 1 60 is a side view, partially in elevation and partially in section, of a portion of a commutator cylinder provided with a short-circuiting device constructed in accordance with our invention. The section is taken along 65 the line I—I of Fig. 2.

Fig. 2 is an end elevational view of the structure illustrated in Fig. 1.

Fig. 3 is an elevational view of one of the detail structures employed in a device constructed in accordance with our invention. 70

In the drawings, we show a commutator cylinder 3 comprising a plurality of spaced insulated conducting segments 4. A disk 5, composed of insulating material and having imbedded therein a plurality of spaced conducting members 6, is mounted upon the end of the commutator cylinder 3. Each of the contact members 6 is provided with a projection 7 which extends into, and is electrically and mechanically attached to, certain of the commutator segments 4. The contact surface of the members 6 is flush with that of the insulating disk 5. 75

The commutator cylinder 3 is mounted 80 upon a shaft 8 upon which is rotatably mounted a disk 9, composed of conducting material, provided with a plurality of spaced contact members 10 which, upon rotation of the disk 9, engage and electrically 85 connect the several contact members 6. A supporting disk 11 is rigidly mounted upon the shaft 8 in spaced relation to the disk 9. Intermediate the disks 9 and 11 is disposed a compression spring 12. This spring serves 90 to cause the contact members 10 on the disk 9 to engage either the contact members 6 or the intermediate insulating surface of the disk 5 with a constant pressure, as the distance between the disks 9 and 11 is never 95 varied. 100

Upon the disk 11 are pivotally mounted two centrifugally actuated weight members 13 by means of pins 14. Each of the weight members is provided with a slot 15 105 within which is disposed a pin 16 mounted

on the disk 9. The weight members 13 are each provided with a pin 17 to which is attached a tension spring 18, the other end of which is attached to the disk 11 by means of 5 a pin 19.

When the machine is operating at a relatively low speed or is idle, the disk 9 and the contact members 10 will remain in the positions illustrated in Fig. 2, that is, with 10 the contact fingers 10 in engagement with the insulating surface intermediate the contact members 6. However, when the machine attains a predetermined speed, the weight members 13 will rotate about their 15 pivotal connections 14 against the action of the tension spring 18 and move to their outermost positions. This movement of the weights causes a rotation of the disk 9 by means of the connection between the pin 16 and slot 15, causing the contact fingers 10 to engage and short circuit the contact members 6.

From the foregoing description, it will 25 be apparent that we have provided a desirable short-circuiting device. One of the chief features of our invention is mounting the insulating disk upon the end of the commutator cylinder and attaching the contact members thereto. As many contact 30 members may be provided as are deemed necessary to properly short circuit the commutator cylinder.

Another advantageous feature of our invention is the use of the compression spring 35 3 in combination with a short circuiting disk subjected to rotative movement only. This combination serves to exert a constant pressure on the disk 9 and, therefore, between the contact fingers 10 and the disk 5 or the contact members 6, as the case may be.

While we have shown and described in detail but a single application of our invention, it will be obvious to those skilled in the art that it is not so limited, but is 45 susceptible of various minor changes and modifications without departing from the spirit thereof, and we desire, therefore, that only such limitations shall be placed thereupon as are imposed by the prior art or as 50 are specifically set forth in the appended claims.

We claim as our invention:

1. In a dynamo-electric machine, a plurality of contact members disposed in annular arrangement, a relatively rotatably mounted member disposed adjacent to said contact members and provided with members adapted to engage said contact members upon movement of said rotatably 60 mounted member, and additional means for maintaining a constant pressure between said contact engaging members and said co-operating members.

2. In a dynamo-electric machine, a disk 65 composed of insulating material and having

a plurality of contact members mounted thereon, a relatively rotatably mounted member disposed adjacent to said disk and provided with contact fingers adapted to engage said contact members when said rotatably mounted member is moved, and independent resilient means for maintaining a substantially constant pressure between said disk and said contact fingers. 70

3. In a dynamo-electric machine, a disk 75 composed of insulating material and having a plurality of contact members imbedded therein, the outer surface of said contact members being substantially flush with the surface of said disk, a relatively rotatably mounted member disposed adjacent to said disk and provided with contact fingers adapted to engage said contact members when said rotatable member is moved, means for actuating said rotatable member under predetermined conditions, and a spring adapted to cause said contact fingers to engage said disk with a substantially constant pressure. 80

4. In a dynamo-electric machine, a disk 90 composed of insulating material and having a plurality of contact members imbedded therein, the outer surface of said contact members being substantially flush with the surface of said disk, a relatively rotatably mounted member disposed adjacent to said disk and provided with contact fingers adapted to engage said contact members when said rotatable member is moved, a spring adapted to cause said contact fingers 95 to engage said disk with a substantially constant pressure, and centrifugally actuated weights connected to said rotatable disk by means of a pin-and-slot connection. 100

5. In a dynamo-electric machine, a disk 105 composed of insulating material and having a plurality of contact members imbedded therein, the outer surface of said contact members being substantially flush with the surface of said disk, a relatively rotatably 110 mounted member disposed adjacent to said disk and provided with contact fingers adapted to engage said contact members when said rotatable member is moved, a spring adapted to cause said contact fingers 115 to engage said disk with a substantially constant pressure, and centrifugally actuated weight connected to said rotatable disk by means of a lost-motion connection. 120

6. In a dynamo-electric machine, a disk 125 composed of insulating material and having a plurality of contact members imbedded therein, the outer surface of said contact members being substantially flush with the surface of said disk, a relatively rotatably mounted member disposed adjacent to said disk and provided with contact fingers adapted to engage said contact members when said rotatable member is moved, a spring adapted to cause said contact fingers 130

to engage said disk with a substantially constant pressure, a centrifugally actuated weight member operatively connected to move said rotatable disk under predetermined conditions, a spring adapted to oppose movement of said weight member, said weight member and said spring being so

arranged that the relative moments thereof change rapidly.

In testimony whereof, we have hereunto 10 subscribed our names this 29th day of January, 1921.

WILLIAM E. OSTERHOUT, M. E.
EWING K. LYNN.
